UNITED STATES PATENT OFFICE.

THOMAS MEAKIN FARMILOE, OF LONDON, ENGLAND.

DESIGN FOR WINDOW-GLASS.

SPECIFICATION forming part of Design No. 36,349, dated June 2, 1903.

Application filed February 5, 1903. Serial No. 142,098. Term of patent 14 years.

To all whom it may concern:

Be it known that I, THOMAS MEAKIN FARMILOE, a subject of the King of England, residing at London, England, have invented a certain new, original, and ornamental Design for Window-Glass, of which the following is a specification.

The accompanying drawing shows a plan view of a portion of window-glass, showing my new design.

What I claim is—

The ornamental design for window-glass, as shown.

In testimony whereof I have signed my name to this specification in the presence of 15 two subscribing witnesses.

THOMAS MEAKIN FARMILOE.
